INVENTOR:

Benno vom Eigen,
BY Draketh ATTYS.

UNITED STATES PATENT OFFICE.

BENNO VOM EIGEN, OF NEWARK, NEW JERSEY.

BAG-LOCK.

SPECIFICATION forming part of Letters Patent No. 336,536, dated February 16, 1886.

Application filed December 4, 1885. Serial No. 184,689. (No model.)

To all whom it may concern:

Be it known that I, BENNO VOM EIGEN, a citizen of Germany, residing at Newark, in the county of Essex and State of New Jersey, 5 have invented certain new and useful Improvements in Bag-Locks; and I do hereby declare the following to be a full, clear, and exact description of the invention, such as will enable others skilled in the art to which it appertains 10 to make and use the same, reference being had to the accompanying drawings, and to letters of reference marked thereon, which form a part of this specification.

The object of this invention is to provide 15 increased security against the surreptitious opening of a bag or satchel; and it consists in the arrangements and combinations of parts, substantially as will be hereinafter set forth, and finally embodied in the clauses of the 20 claim.

Referring to the accompanying drawings, in which like letters indicate corresponding parts in each of the several figures, Figure 1 is a side elevation of a bag or satchel lock. Fig. 25 2 is a vertical section of the same, taken longitudinally. Fig. 3 is a bottom view of the lock, the bottom plate being removed to show the interior mechanism; and Figs. 4 to 7 illustrate in detail certain parts which will be fully 30 described.

In said drawings, *a* indicates a lock-case adapted to be secured on a bag-frame section or jaw in any ordinary manner. *b* is a bolt or sliding catch, which works in said case, having 35 catching edges or projections *c c*, which engage ordinary holding tongues or lugs on the co-operating jaw or section of the frame, which lugs enter the said case through openings or perforations *d d* in the latter. (Shown 40 in Fig. 1.)

Connected with the bolt or sliding catch, to operate the same, is a finger-piece, *e*, which is arranged in a barrel or tubular section, *f*, arranged longitudinally upon the case, and secured 45 thereon by suitable rivets or pins or staples, *g*, at one end, and at the other end by being inserted in a central, vertical, and hollow stud or shaft-bearing. The said finger-piece moves in a direction parallel with the 50 bolt, and is connected with the said bolt by means of a pin or rivet, *g'*, so that when press-

ure is brought to bear on the end of the finger-piece the bolt is moved from a holding position or relation to the tongues before referred to, the barrel and case being slotted, as at *h h*, 55 to allow the movement of the pin. A return movement is given to the bolt, whereby it may pass automatically into catching engagement by a spring, *i*, arranged between the end of the bolt and the case. At about the 60 middle of the case, projecting upward therefrom, is secured the vertical tube or shaft-bearing *K*, before mentioned, which provides bearings for the inner ends of the barrels or pieces *f s*, and acts as a sleeve for a locking- 65 shaft, *l*. Said locking-shaft is adapted to turn in the said sleeve when operated by a removable key or finger-piece, *m*—such as is shown in side and front elevation in Figs. 4 and 5—or by a permanently-attached finger-piece, *n*. 70 (Shown in Fig. 2 and in detail in Fig. 6.) The lower end of the shaft *l* enters a recess, *o*, Figs. 3 and 7, in the top of the bolt, and is therat provided with a lateral projection, *p*, which, when turned in a transverse direction, 75 as indicated in outline in Fig. 7, allows the bolt to move longitudinally, so that the frame-sections may be unlocked by pushing the finger-piece *e*; but when turned in a longitudinal direction, as in Fig. 3, the said projection *p* strikes one of the end walls of the recess, and the said bolt is held in catching engagement with the lugs or tongues of the opposite frame-section, as will be understood. Said lower end of the shaft is also provided 80 with a projection, *t*, to engage the spring *v*, so that a greater exertion of power will be required in turning the shaft from a locked to an unlocked position. Said projection *t* is made shorter than the lock-projection *p*, as indicated in Fig. 6, so that the said projection *t* 85 will clear the bolt and allow a further movement thereof. Said shaft at its lowest extremity is provided with a bearing, *q*, Figs. 2, 4, and 6, which enters a suitable seat or bearing in a 90 bottom plate, *u*, of the lock-case. At the opposite side of the vertical tube from the barrel *f* is secured a piece, *s*, which acts as a bearing for one finger of the hand, as the pushing-finger thereof bears or presses on the finger-piece *e*, said piece *s* having one end secured 95 in the tube *K*, and the other end riveted to the 100

case by the rivet or staple *j*. The locking-shaft is held in its locked and unlocked positions by a spring, *v*, as illustrated in Fig. 3. Said spring bears against the sides of the shaft, 5 which is flat or angular, and holds it in the desired position. The ends of the spring preferably bear against the side walls of the lock-case, as shown.

To one understanding the operation of the 10 lock its manipulation is convenient and easy, while to one unacquainted with it it presents difficulties in opening the satchel which require time to avoid, so that a hasty theft from the satchel while the owner's attention is 15 called for the moment away from it is prevented.

Having thus described the invention, what I claim as new is—

1. The combination of the lock-case, recessed bolt, finger-piece *c*, a locking-shaft having a locking-projection, a spring for holding the said shaft, and a spring, *i*, for returning the bolt, all substantially as shown and described.

2. The improved bag-lock, combining 25 therein the case *a* having openings *d d* and *h*, the vertical sleeve or bearing *k*, the barrel *f*, locking-shaft *l*, having projection *p*, and permanently attached finger-piece *n*, the finger-piece *e*, arranged in said barrel and connected

with the bolt by a pin or portion, *g'*, a spring, 30 *v*, for holding the shaft, and a spring, *i*, for operating the bolt, all said parts being arranged and combined substantially as set forth.

3. In combination with a lock-case for satchels, a bolt having a recess, *o*, and a shaft for 35 locking said bolt, having at its lower end a locking-projection to engage the end wall of the said recess and projecting vertically through said case, and at the outer or upper end provided with a permanently-secured 40 finger-piece, *n*, substantially as herein set forth.

4. The combination, with the case *a*, sleeve *K*, and barrel *f*, arranged substantially as shown and described, of a recessed bolt, *b*, working in said case, a finger-piece, *e*, working 45 in said barrel and operating the bolt, and a locking-shaft, *l*, working in said sleeve and locking said bolt, all said parts being arranged and adapted to operate substantially as herein set forth.

In testimony that I claim the foregoing I have hereunto set my hand this 19th day of November, 1885.

BENNO VOM EIGEN.
